UNITED STATES PATENT OFFICE.

THEODORE B. BECKLEY, OF NEW ORLEANS, LOUISIANA.

COLLAR BUTTON AND CLASP.

1,421,148.

Specification of Letters Patent. Patented June 27, 1922.

Application filed September 18, 1920. Serial No. 411,038.

To all whom it may concern:

Be it known that I, THEODORE B. BECKLEY, a citizen of France, residing at New Orleans, in the parish of Orleans and State 5 of Louisiana; have invented certain new and useful Improvements in a Collar Button and Clasp; and I do hereby declare the following to be a full, clear, and exact description of the invention, such as will enable others 10 skilled in the art to which it appertains to make and use the same.

This invention relates to a collar button and clasp, and the object is to provide for effectively securing the collar in position, 15 regardless of the exact size of the button hole, the device comprising an inner element, an outer element or head, a shank, formed in one or more sections, and resilient elements for engaging respectively the collar band, and the inner and outer surfaces 20 of the collar.

A further object is to provide a device which may be quickly applied, and detached, without danger of spoiling the 25 appearance of the collar by partly crushing or rumpling any portion thereof, and a device which will present a neat appearance.

A still further object is to provide, in another form of the button and clasp, means 30 for hingedly or pivotally connecting the elements which directly engage the shirt band and engage both sides of the collar adjacent to the ends thereof.

A still further object is to provide, in a 35 further form, a flexible element, such as a chain, connected with the detachable head and with the inner portion of the button which engages the inner surface of the shirt band.

With the foregoing and other objects in 40 view, the invention consists in the novel construction, combination and arrangement of elements hereinafter described and claimed.

In the accompanying drawings:

Figure 1 is a view in elevation of one 45 form of the device, with parts broken away.

Figure 2 is a view in side elevation, with 50 portions broken away and showing snap fastening devices for securing certain of the elements, mentioned below.

Figure 3 is a view in side elevation of a 55 form showing a shank made in one piece and adapted for threaded connection with the rotatable head, the elements forming the clasp being pivotally connected.

Figure 4 is a view of this construction in front elevation.

Figure 5 is similar to Figure 3, the shank in this case being formed in two parts however.

Figure 6 is a view in side elevation of a 60 form showing pivotally connected members, one of which carries a single shank element, the latter being adapted for ball and socket connection with the head.

Figure 7 shows a construction similar to that illustrated in Figure 6, except that the head is rotatable and has threaded connection with the shank.

Figure 8 is a fragmentary view in vertical section, showing the device in operative position and connected with the shirt band and collar.

Figure 9 is a side elevation, illustrating a 70 form of my invention in which a chain or similar flexible element connects the detachable head with the base.

Figure 10 is a side elevation of a rotatable fastening head which may be employed.

Figure 11 is a rear view of one form of 80 base.

Figure 12 is a rear view of one form of supporting bar.

Figure 13 is an elevation of one form of 85 clasp arm.

Figure 14 is a view partly in side elevation and partly in section of the clasp arm of Figure 13, and

Figure 15 is a side elevation of the bar of 90 Figure 12.

Referring especially to the form shown in Figure 1, the base or inner element of the button is designated 10, being of elliptical or other suitable form. Connected with the base is an element of resilient material, comprising two hook portions and two straight portions, the former being shown at 12 and 13, and the latter at 14 and 15. In this form, the shank comprises two sections 16 and 17, and the button head 18 completes 100 the construction.

The extreme end portion of the hook 12 is rigidly connected with the base 10, and the inner shank section 16 is formed with a rounded end received by the socket 21 in 105 element 14, the parts being normally in contact owing to the resiliency previously mentioned.

The shank section 17 rigidly connected with element 14 is also provided with a 110

rounded end received by a socket 22 in the element 15, the shank sections 16 and 17 of course being in alignment. In this form the head 18 is permanently secured to the element 15.

In the fragmentary section illustrated in Figure 8, it will be observed that the intermediate vertical bar, corresponding with the element 14 in the form above described, 10 is positioned between the shirt band and the inner end element of the collar, when the latter is secured in position. The U-element of the device is illustrated in Figure 1 and elsewhere, permits of the separation of 15 the parts by slight pressure on the fingers, and the parts return to correct position with the ends of the collar engaged, and properly secured to the collar band of the shirt. This 20 general principle of operation applies to all forms of the device.

In the form shown in Figure 2, the only important difference is that the shank, formed in two pieces, connects with the resilient devices by means of snap fastenings, 25 the ball elements 25 and 26 cooperating with the socket portions 27 and 28.

In Figure 3, the base 30 is provided with an offset element 31 having pivotal connection at 32 with a central vertical bar 33 30 provided with a central slot 34, for receiving the single shank 35 having a notch 36 therein engaging the edge portion of the slot in element 33. The shank is provided with a threaded end 37 engaged by a head 38 35 also threaded, internally, for engagement with the threads first named.

The bar 33 is pivotally connected at 40 with a short bar 41 having an apertured end 42 for receiving the grooved portion 43 of 40 the head. The head is thereby permitted to rotate with reference to the short arm of the clasp in which it is mounted, but is not detachable from this arm after having been mounted therein. The operation is apparent, in view of the operation of the form first described. In Figure 5 head 45 is fixed on bar 45'.

The form shown in Figure 6 corresponds in essential particulars with the form shown 50 in Figure 3, except that the shank 47 is provided with a rounded element 48 adapted to be received by the socket 49, forming the

ordinary snap fastening. The rigidly mounted head is designated 50.

Figure 7 shows the construction of Figure 55 3, the elements of the button and clasp being in open position.

In the form shown in Figure 9, the base 51 serves to mount a shank 52 formed with one element 53 of the snap fastening, the cooperating element 54 being carried by the head 55. A flexible element, such as a chain 56 connects the head 55 with the base, the chain assuming the position shown in this figure when the device is in operative position. 65

Having thus described the invention what I claim is:—

1. A device of the class described having a supporting bar, clasp arms movable relatively thereto disposed on opposite sides 70 thereof, retaining means on one of the arms to extend across the bar, and means to secure the retaining means to the other arm.

2. A device of the class described having a supporting bar, clasp arms on opposite 75 sides thereof, said bar having a slot, a retaining member extending from one of the arms and removably passable through said slot to bridge the arms, and said member having a notch to cooperate with the bar. 80

3. A device of the class described having a supporting bar, clasp arms on opposite sides thereof, said bar having a slot therein, a stud extending from one of the arms to pass through said slot, said stud having 85 a shoulder to engage the bar, and separable fastening means between the stud and the other arm including a turnable head on the latter arm.

4. A device of the class described having 90 fastening heads movable away from each other, a connecting means for the heads, and a supporting and fastening means extending from one head separably from and across the supporting and fastening means, and a 95 separable connection between the other head and said supporting and fastening means.

In testimony whereof I affix my signature in presence of two witnesses.

THEODORE B. BECKLEY.

Witnesses:

OTTO D. DONALDSON,
A. HEWITT.
